UNITED STATES PATENT OFFICE

NICHOLAS LAWNER AND SAMUEL DUBERSTEIN, OF BROOKLYN, NEW YORK, ASSIGNEES
TO AMERICAN SUNDRIES CO. INC., OF BROOKLYN, NEW YORK

VAPORIZER

Application filed January 2, 1933. Serial No. 584,490.

This invention relates to electric vaporizers of the type described and shown in the earlier patents of Nicholas Lawner #1,625,034 and #1,663,558.

With vaporizers of this type the vapor passing out through the spout and to be inhaled by the patient disperses in all directions and in order to prevent this the patient often has to use a towel or other means to be placed around the head and hold it over the spout so that the vapors will be directed toward the mouth or nose of the patient. Such method is inconvenient and inasmuch as the vapors also strike other parts of the face and eyes of the patient the use of the vaporizer is rendered objectionable.

It is, therefore, one object of our invention to provide the electric vaporizer with means for deflecting the vapors so that they will be directed toward the nose and mouth of the user and render the use of the vaporizer more effective and more comfortable.

Another object is to so construct said means that the same can be conveniently moved into or adjusted to the position desired.

A still further object is to provide a construction which will permit the positioning of the said vapor deflecting means so as to facilitate the packing, shipping and storing of said vaporizer.

Still another object is to provide effective means for preventing the separation of the receptacle and its lid while the current is on, so as to protect the user against touching the heating element or receiving a shock.

With these and other objects in view our invention consists in the novel construction, arrangement and combination of parts as will be hereinafter more fully described, shown and defined in the appended claims.

In the accompanying drawings which form part of this specification and in which similar reference characters denote corresponding parts;

Fig. 1 is a side elevational view of one form of our device;

Fig. 2 is a top plan view;

Fig. 3 is a rear elevational view;

Fig. 4 is a partial side elevational view illustrating in full lines one position of our

deflecting means on the vaporizer, and in dotted lines, the position of said means for removal of the lid of said vaporizer;

Fig. 5 is a further side elevation illustrating the relationship of elements in packing 55 position;

Fig. 6 is a partial sectional elevation of a modification of our first embodiment;

Fig. 7 is a partial side elevation of a further modified form of our device; 60

Fig. 8 is a top plan view of the modification of Fig. 7,

Figs. 9 and 10 are respectively elevation and plan views of a third modification;

Fig. 11 is a perspective view of a fourth 65 modification;

Fig. 12 is a side elevational view of a fifth modification;

Fig. 13 is a partial sectional side elevation of a sixth modification; 70

Fig. 14 is a partial sectional side elevation of a seventh modification; and

Fig. 15 is a top plan view of the modification of Fig. 15.

Fig. 16 is a side elevation of a further 75 modification, in which the deflector is attached to the electric plug.

Referring to the drawings and first to the construction shown in Figs. 1 to 5, 10 denotes the conventional liquid receptacle, such as a 80 glass jar which may be of square cross section as shown, or other suitable shape. 11 denotes a lid removably mounted thereon, such as by threads. 12 denotes a suitable electric heater consisting in this case of a pair of two carbon 85 electrodes 13 carried by metal rods 14 suitably fixed to and insulated from the lid 11 to project therefrom downwardly into the receptacle. The upper ends of said rods 14 project upwardly from the lid and constitute 90 electric terminals 15 for the engagement of an electric plug P or other electric connecting means. 16 denotes a vapor conduit, such as a spout as shown, for the passage of the vapor produced in the receptacle. 17 denotes 95 a support or stand for the receptacle to keep the latter in steady position when in use. This support comprises a base 18 provided with a marginal gripping flange 19 to sufficiently engage the lower part of the receptacle 100

or jar as to steady its position on said support. Projecting from and fixed to said base in a suitable manner is a vertical post or bar 20 adapted to extend centrally along the rear side of the receptacle and provided with a handle 21 and a hoop shaped bracing member 22 which is adapted to embrace the neck of the receptacle when the latter rests on the base 18 of the support.

10 Thus far the construction of the device is similar to that described in the above patents. Now, when using a vaporizer of this kind, the patient places the jar as close to his face as possible so that the vapors passing out from 15 the spout can be inhaled through his mouth and nose. But inasmuch as the vapors tend to disperse in all directions the patient often resorts to a towel or the like covering for his head and the nozzle to thereby direct the 20 vapors as desired. But the same also strikes other parts of the patient's face affecting his eyes and making him feel uncomfortable.

To remedy this drawback we provide a vapor deflector 23. This deflector is in form 25 of a scoop or the like and is movably attached to vertical side posts 23' fixed to the base so as to be capable of being positioned to extend over the spout in the desired direction, and when not in use to extend in a vertical position 30 for facilitating packing, shipping and storing of the vaporizer. In the present example a pair of collapsible member 24 are used as attachment means, the same being pivotally attached to each other at 24^a, to the 35 deflector at one end as at 24^b and to the vertical posts or bars as at 24^c at the other end. In Fig. 1 the deflector is shown in position of use and in Fig. 5 in collapsed position for packing or storing purposes.

40 Another drawback of the hitherto used construction is that the separation of receptacle and lid, or the removal of the lid from the receptacle, while the current is on, is not positively prevented. In the construction 45 described in the aforementioned patents the holding of the receptacle and lid together is depended upon the member 22 and a loop formed on the rear post 20 of the support and through which the plug is passed when engaging the terminals 15. Owing to the natural or given resiliency of the member 22 and that of the loop the receptacle can when 50 exerting a slight pull in the upward and forward directions be brought into a position 55 where it can be separated from or unscrewed from the lid, without pulling off the plug, as a result of which the patient is liable to receive a shock or be injured by the exposed electrodes. To do away with this drawback 60 we have provided a locking means whereby under no circumstances could the receptacle and lid be separated while the plug is on.

In the example shown in Figs. 1-5 the deflector itself may at the same time serve 65 as a lock. Here while the deflector extends

over the spout, it prevents the receptacle and lid from being moved vertically or turned to be unscrewed from one another as in cooperation with the spout it obstructs such movements. But if the deflector is collapsibly supported, as in the present example, the link arms 24^a connected to the side posts 23 may be limited by stops 25 on posts 23' against turning downwardly in one direction more than a desired extent, so that they will always be in the path of the spout when the lid is turned and as long as the plug is in engagement with the terminals. But when the plug is removed the deflector and link arms 24^a can be tilted rearwardly as shown in dotted lines in Fig. 4, which will permit the removal of the lid for filling purposes.

It thus is clear that unless the plug is off, the lid will be positively locked in closing position.

In Fig. 6 we have shown a modification in which the deflector when moved into the collapsed position is capable of automatically pushing the plug off the terminals. To this end the deflector 23^a at its rear edge is provided with an extension finger 26 which in position of use bears below the plug. When the deflector is tilted into the collapsed position shown in Fig. 5 the finger 26 will engage the lower face of the plug and push the latter off the terminals.

In Figs. 8 and 9 a modification is shown in which the lifting finger is not connected with the deflector. Here the rear post 20 has an upper extension to which is hingedly or pivotally attached a manually operable finger 27 the inner end 27^a of which extends toward and bears below the plug and the other end 27^b of which serves as a press finger. As long as the finger 27 is in position below the plug it prevents the lifting and turning of the receptacle and lid or either of them. But when it is desired to separate the receptacle and lid or remove the latter the outer end 27^b of said finger is depressed, thereby pushing off the plug and simultaneously releasing the lid. The finger may be spring actuated (the spring not being shown).

In Figs. 9 and 10 a further modification is shown. Here the handle 28 is not formed on a vertical rear post as in Fig. 1 but as a U-shaped cross piece. The extreme ends of said cross piece are adapted to engage slits 29^a in the upper cylindrical ends 29^b of vertical side bars or posts 29 fixed to the base of the support. The cross bar is held in position in said slits by nuts 30 threading on said cylindrical ends 29^b. The cross handle prevents the separation of receptacle and lid either by its ends 28^a bearing tightly on the lid or by being in the path of the terminals and plug or spout when the lid is rotated.

In Fig. 11, another modification is shown. Herein there are provided on the lid 11 straps

or loops 31 into which prongs or tenons 32 integrally formed with or attached to deflector 23^b may be inserted and are adapted to be frictionally retained therein. The deflector is thus removably mountable on the lid over the spout 16.

In Fig. 12 still another modification is shown. Herein the liquid receptacle is adapted to be mounted in a stand which has a base 33 and uprights 34 (only one of which is shown) at opposite sides of said base. Prongs or supporting tongues 35 are provided on the deflector 23^c which may be attached to the respective uprights 34 by bolting as at 36 or the like. Said deflector 23^c is thus likewise removably mountable from over the spout 16. Said prongs 35 could be also connected to the uprights 29 of Figs. 9 and 10.

20 In Fig. 13 still a further modification is disclosed. Herein, there is mounted on the deflector 23^d at or near its rear end, a socket 37 having an opening 38 therein tapered to correspond with the taper of spout 16. To mount said deflector merely requires pushing of socket 37 onto spout 16 until they are firmly wedged together. Thus this deflector is likewise removable from over the spout opening.

25 Figs. 14 and 15 show still another modification. Herein, the usual spout is omitted from the lid 11. An opening 39 is provided in said lid however. A ring 40 is provided with a plurality of downwardly projecting prongs 41 which latter are adapted to grip the external side of the lid 11 and frictionally be retained thereon. Prongs or tenons 42 are provided on a deflector 23^e which are permanently attached to ring 40. In use the latter is mounted on lid 11 by means of prongs 41 so that opening 39 is covered by deflector 23^e. Thus vapor emerging from said opening is spread about said deflector. The latter is, of course, removable with its ring 40.

30 Other modifications are, of course, possible without departing from the principle of our invention and we therefore, do not wish to limit ourselves to the details described and shown.

35 Thus for instance, the deflector 23^f may be attached at 40 to the electric plug *p* engaging the terminals projecting from the lid 11 of the receptacle 10, as shown in Fig. 16.

What we claim is:

1. In a vaporizer, the combination of a liquid receptacle having a vapor passage, a support for said receptacle and means carried by said support to extend over said vapor passage for deflecting the vapors on issuing from said passage in the desired direction.

2. In a vaporizer, the combination of a liquid receptacle having a vapor passage, a support for said receptacle, vapor deflecting means and a link connection between said means and said support enabling the posi-

tioning of said means over said passage for deflecting the vapors in the desired direction.

3. In an electric vaporizer, a liquid receptacle having a removable lid formed with a vapor passage, an electric heater in said receptacle formed with terminals projecting through said lid outwardly for the engagement of an electric plug and a movable vapor deflecting means over said vapor passage, which while the plug is on the lid will prevent the removal of the latter.

4. In an electric vaporizer, a liquid receptacle having a lid threadedly mounted thereon and formed with a vapor passage, an electric heater in said receptacle having terminals projecting outwardly through said lid for the engagement of an electric plug and movable means associated with said receptacle and capable of being so positioned relative to said lid as to prevent the separation of said receptacle and lid as long as the plug is in engagement with said terminals.

5. In an electric vaporizer, a liquid receptacle with a lid threadedly mounted thereon and having a spout, an electric heater suspended in said receptacle and having terminals projecting through said lid outwardly for electric connections with said heater and movable means associated with said receptacle and which while the terminals bear the electric connections will project into the path of rotation of said lid and spout preventing the removal of said lid from the receptacle.

6. In a vaporizer, a liquid receptacle with a lid threadedly mounted thereon and having a spout, a movable vapor deflecting element associated with said receptacle and capable in position of use of engaging said spout to lock said lid in closing position.

7. In a vaporizer, a liquid receptacle with a lid threading thereon and having a spout, a support for said receptacle, removable means carried by said support and adapted in position of use to engage said spout so as to lock said lid in closing position.

8. In a vaporizer, a liquid receptacle with a removable lid and a projecting vapor passage, means for supporting said receptacle and removable means on said supporting means adapted in position of use to cooperate with said vapor passage to lock said lid in closing position.

9. In a liquid heater, a liquid receptacle, a lid threadedly mounted thereon having a projecting element, a support for said receptacle and means associated with said support and adapted in position of use to cooperate with said projecting element to prevent the unscrewing of said lid from the receptacle.

10. In a vaporizer, a liquid receptacle, a lid threadedly mounted thereon and having a projecting vapor spout, a support for said receptacle, a vapor deflecting element carried by said support and capable in position of

use of cooperating with said spout when said lid is rotated to prevent the unscrewing of said lid from the receptacle.

11. In a vaporizer, a liquid receptacle having a vapor passage, and a movable vapor deflecting means capable of being moved into position over said passage when in use and folded when not in use.

12. In a vaporizer, a liquid receptacle having a vapor passage, a support for said receptacle, a vapor deflecting means linked to said support so that it can be positioned over said passage when in use and folded when not in use.

13. In an electric liquid heater, a liquid receptacle having a removable lid, an electric heating element therein having terminals projecting from the top thereof for engagement of an electric plug, and means associated with said receptacle and capable of locking said lid in closed position when the heater is in use and of being moved to release said lid after the removal of said plug.

14. In a vaporizer, a receptacle having a removable lid, a support for said receptacle and manually operable means on said support which in position of use will lock said lid in closing position on said receptacle.

15. In a vaporizer, a receptacle having a removable lid, a support for said receptacle and manually operable vapor deflecting means on said support which in position of use will lock said lid in closing position on said receptacle.

16. In an electric vaporizer, a liquid receptacle having a removable lid formed with a spout, an electric heater, in said receptacle having terminals projecting outwardly from said lid for the engagement of an electric plug and a vapor deflecting means adapted in position of use to extend over said spout for deflecting the vapors and preventing the removal of the lid and capable of being collapsed for the purpose of packing or storing.

17. In a vaporizer the combination of a receptacle having a lid with a vapor passage therein and a removable vapor deflecting means to cooperate with said vapor passage.

18. In a vaporizer, the combination of a receptacle having a lid with a vapor passage therein and a vapor deflecting means removably attached to said lid.

19. In a vaporizer, the combination of a receptacle having a vapor passage, a heater in said receptacle with terminals projecting through the top of said receptacle, an electric plug for engaging said terminals and a vapor deflecting means on said plug to extend over said vapor passage.

20. In testimony whereof, we affix our signatures.

NICHOLAS LAWNER.
SAMUEL DUBERSTEIN.
